UNITED STATES PATENT OFFICE.

LELAND WILLIS, OF GRENLOCH, NEW JERSEY, ASSIGNOR TO BATEMAN MANUFACTURING COMPANY, OF GRENLOCH, NEW JERSEY, A CORPORATION OF NEW JERSEY.

DESIGN FOR A POTATO-PLANTER FRAME.

46,614.

Specification for Design.

Patented Oct. 27, 1914.

Application filed July 17, 1914. Serial No. 851,649. Term of patent 14 years.

To all whom it may concern:

Be it known that I, LELAND WILLIS, a citizen of the United States, residing in Grenloch, Camden county, New Jersey, have invented a new, original, and ornamental Design for a Potato-Planter Frame, of which the following is the specification.

My design is shown in the accompanying drawing, which shows a perspective view of the potato planter frame.

I claim:

The ornamental design for a potato planter frame substantially as shown.

LELAND WILLIS.
